(57) **CLAIM**

I claim the ornamental design for a food bowl vacuum formed from laminar polymeric plastic resin, as shown and described.

DESCRIPTION

FIG. 1 is a top isometric view;
FIG. 2 is an alternative top isometric view;
FIG. 3 is a bottom isometric view;
FIG. 4 is an alternative bottom isometric view;
FIG. 5 is a top plan view;
FIG. 6 is a bottom plan view;
FIG. 7 is a side view with the opposite side being a mirror image;
FIG. 8 is another side view with the opposite side being a mirror image;
FIG. 9 is an enlarged top isometric view shown broken away for ease of illustration;
FIG. 10 is another enlarged top isometric view shown broken away for ease of illustration;
FIG. 11 is another enlarged top isometric view shown broken away for ease of illustration;
FIG. 12 is enlarged top isometric view shown broken away for ease of illustration;
FIG. 13 is an enlarged bottom isometric view shown broken away for ease of illustration; and,
FIG. 14 is an enlarged bottom isometric view shown broken away for ease of illustration.
The dash-dot-dot lines in FIGS. 9 through 14 are truncation lines which delineate the physical end of a cut form no part of the claim.
